Inventor:

Geo. M. Hubbard.

UNITED STATES PATENT OFFICE.

GEORGE W. HUBBARD, OF WINDSOR, VERMONT.

MACHINE FOR SETTING GLAZIERS' POINTS.

SPECIFICATION forming part of Letters Patent No. 252,879, dated January 17, 1882.

Application filed January 22, 1880.

To all whom it may concern:

Be it known that I, GEO. W. HUBBARD, of Windsor, in the county of Windsor and State of Vermont, have invented a new and useful Improvement in Machines for Setting Glaziers' Points, of which the following is a specification.

The invention relates to machines used for setting the sheet-metal points used by glaziers for securing glasses in window-sash before putting.

Heretofore such machines have been constructed for inserting the points into the sash by pressure. This method is objectionable, for the reason that it requires a clamping or fastening of the machine to the sash to resist the reaction of the pressure against the point necessary for its insertion, thus rendering the operation comparatively slow.

The object of my invention is to provide a glazier's-pointsetter which will drive the points without the necessity of clamping the machine to the sash, and which will do this accurately in direction and depth and in close contact with the face of the glass, and which will be readily adjustable in the force of its blow, according to the varying hardness of the wood of the sash.

The invention consists in a striker moved backward by the action of a lever and forward by the reaction of a spring.

It also consists in the connection, with said striker, of a driving-plate, said plate also forming an opening and closing bottom to the receptacle containing the points to be driven.

It also consists in an adjustable latch, by which the force of the blow driving the point may be regulated.

In the accompanying drawings, in which similar letters of reference indicate like parts, Figure 1 is a side elevation and partial section on the line A B, Fig. 2, of a device embodying my invention; Fig. 2, a plan view of the same; Fig. 3, a partial vertical longitudinal section of the striker; Fig. 4, a vertical longitudinal section of the striker-plate and portions of parts connected therewith; Figs. 5 and 6, plan and end elevation of the striker-plate.

O C', Figs. 1 and 2, is the main frame of the machine; a a, the receptacle for the points to be driven; D D, Figs. 1 and 2, a lever, pivoted

at E, Figs. 1 and 2, in the open part C of the frame O C'.

In Fig. 1, F is the striker; G, a spring forcing the striker in the direction of the arrow; H, a latch, pivoted at its middle and supported at its forward end by the spring k, so as to engage with the end d of the lever D D, the amount of its engagement or lap upon the end d being adjustable by means of the screw I, tapped through the rear end of the latch H. 55 The spring R serves to throw the lever D D downward.

K, Fig. 1, is the striker-plate, which is firmly riveted to the bottom of the striker F.

In Figs. 4, 5, and 6, L represents a plate, 65 which is riveted to the frame O C' at the bottom of the receptacle a. This plate has an opening, l, through it, and conforming to the receptacle a. The striker-plate K slides laterally in close contact with the lower face of the plate 70 L, being held in such contact by the folding of the edges of the striker-plate upward and around the edges of the plate L, as shown at k k k, Fig. 6. The opening l in the plate L conforms also to the shape of points in the receptacle a. A notch or recess, m, is made in the front edge of the striker-plate K, of a proper shape and of depth sufficient to receive that portion of the point which is desired to project from the sash after driving. 75

A cross-bar, M, of wood or other soft material, is fastened across the bottom of the rear end of the frame O C', to insure its uprightness upon the glass and to prevent contact of the metal portion of the frame with the glass. 80

P is a rod or follower for pressing the points downward in the receptacle a a.

N represents a portion of ordinary window-sash; O, its glass in proper position.

The operation of the device is as follows: 90 The rod P being removed, the points are placed regularly in the receptacle a, and the rod P is then replaced, as in Fig. 1. The operator then grasps the machine with one hand about the part c e, the fingers extending below and embracing the part s s of the lever D D, and places the machine upon the glass O, as shown in Fig. 1, pressing downward and forward against the sash N. With the other hand he presses downward upon the rod P; then, forcibly closing the 95

hand embracing the parts *c c* and *s s*, the lever *D D* is drawn into the position *D' D'*. (Shown in dotted lines in Fig. 1.) By the lap of the end *d* of the lever *D* upon the end of the latch *H* the striker *F* is thus forced backward against the action of the spring *G*. The striker-plate *K* is also drawn backward sufficiently to uncover the opening *l* in the plate *L*, Figs. 4 and 5. The pressure upon the rod *P* then causes 10 the points in the receptacle *a* to move downward until the lowest point rests upon the glass *O* in front of the withdrawn striker-plate *K*, which is of thickness about equal to that of a single point. The end *d* of the lever *D D*, by 15 reason of the position of the pivot *E*, has an upward as well as a longitudinal movement, and at a certain position this upward movement causes the end *d* to withdraw and become disengaged from the end of the latch *H*. This dis- 20 engagement allows the striker *F* and its plate *K* to fly forward forcibly under the reaction of the spring *G*. The point, which had already been resting upon the glass *O* in front of the striker-plate *K*, is caught in the recess *m*, Fig. 5, 25 and is then carried forward to and driven into the sash *N*. The end *T T* of the striker-plate, coming into contact with the sash *N*, serves to prevent the point from being driven farther into the sash than is desired. The bottom point 30 having been driven as above described, the grasp upon the lever *D* is slackened, and by the action of the spring *R* the said lever is carried to its original position *D D*, in its move- 35 ment passing over and depressing the latch *H*, as shown in Fig. 3. The end *d* having cleared the end of the latch *H*, the latter is pressed upward and re-engaged with the end *d* by means of the spring *h*.

Repetitions of the above operation drive the remaining points successively. 40

By turning the screw *I*, Fig. 1, the elevation of the opposite end of the latch *H* may be regulated, and in this manner the distance which the lever *D* carries back the driver *F* before disengagement with the latch *H*, and consequently the force of the blow given by striker, 45 is rendered readily adjustable.

By reason of the quickness of the blow given and the resistance to its reaction afforded by the weight of the machine and the forward 50 pressure by the hand of the operator, any fastening or clamping of the machine is rendered unnecessary.

What I claim is—

1. In a glazier's-point setter, the combination 55 of the spring *G*, the striker *F*, and driving-plate *K*, substantially as and for the purposes set forth.

2. In a glazier's-point setter, the combination 60 of the lever *D*, striker *F*, and driving-plate *K*, substantially as and for the purposes set forth.

3. The combination, with a receptacle for glaziers' points, of a driving-plate, which also forms an opening and closing bottom for the 65 said receptacle, substantially as set forth. 5

4. The vibrating latch or key *H*, in combination with the striker *F* and lever *D*, substantially as and for the purposes set forth.

5. The adjusting-screw *I*, in combination with the latch or key *H*, striker *F*, and lever *D*, substantially as and for the purposes set forth. 70

GEO. W. HUBBARD.
